(57) **CLAIM**

The ornamental design for an tessellatable brick, as shown and described above.

DESCRIPTION

FIG. 1 is a perspective view of a tessellatable brick of the present invention with beveled front edges;

FIG. 2 is a top view of the brick of FIG. 1;

FIG. 3 is a front plan view of the brick of FIG. 1;

FIG. 4 is a right side view of the brick of FIG. 1;

FIG. 5 is a rear plan view of the brick of FIG. 1;

FIG. 6 is a left side view of the brick of FIG. 1;

FIG. 7 is a bottom plan view of the brick of FIG. 1; and,
FIG. 8 is a top plan view of a plurality of bricks according to FIG. 1 arranged together in a tessellating pattern therefor. The broken line showing of the other bricks in FIG. 8 is for illustrative purposes only and forms no part of the claimed design.
